L. I. BRUCE CLOCKCASE

Des. 124,829

Filed Nov. 15, 1940

Invention:
Leo Ivan Bruce,
by Many C. Jenkins
His Attorney

UNITED STATES PATENT OFFICE

124,829

DESIGN FOR A CLOCKCASE

Leo Ivan Bruce, Framingham, Mass., assignor to Warren Telechren Company, a corporation of Maine

Application November 15, 1940, Serial No. 96,592

Term of patent 7 years

To whom it may concern:

Be it known that I, Leo Ivan Bruce, a citizen of the United States, residing at Framingham, in the county of Middlesex, State of Massachusetts, have invented a new, original, and ornamental Design for a Clockcase, of which the following is a specification, reference being had to the accompanying drawing, forming a part thereof.

The figure is a front perspective view of a clockcase showing my new design.

I claim:

The ornamental design for a clockcase, as shown.

LEO IVAN BRUCE.
